UNITED STATES PATENT OFFICE.

NORMAN V. CHRISTENSEN AND WALTER M. HANNEMAN, OF CHICAGO, ILLINOIS, ASSIGNEES TO UNION SPECIAL MACHINE COMPANY, OF CHICAGO, ILLINOIS, A CORPORATION OF ILLINOIS.

FILLED-BAG-CLOSING MACHINE.

Application filed May 21, 1926. Serial No. 110,696.

The invention relates to new and useful improvements in filled bag closing machines, and more particularly to a filled bag closing machine wherein the sewing head may be 5 moved relative to the filled bag during the stitching of the mouth of the bag.

An object of the invention is to provide a filled bag closing machine wherein the sewing head and the actuating means therefor is 10 mounted on a carriage, which carriage can be removed from the tracks on which the carriage travels as a unit, without in any way disturbing the devices whereby the operator controls the actuation of the sewing head and 15 the operation of the actuating devices.

A further object of the invention is to provide a filled bag sewing machine of the above type wherein the sewing head is driven by the motor and the motor and sewing head are 20 so mounted on the carriage that the weight of the carriage unit is center near the main front rail of the track, so that the motor may be utilized to counterbalance the weight of the overhanging sewing head.

25 A further object of the invention is to provide a machine of the above type wherein the tracks may be bodily moved toward or from the front of the machine for positioning the sewing head so that the sewing head 30 may be placed to travel at different distances from the frame of the machine and thus properly positioned for stitching different sized bags.

35 A further object of the invention is to provide a machine of the above type wherein the rails along which the carriage travels are inclined toward the initial starting point for the sewing of the bag, whereby the carriage may be returned by gravity after the bag is 40 closed, and to provide in addition thereto, means in which power is stored during the stitching of the bag to bring about the initial starting of the carriage on its return and for facilitating its return to its initial starting 45 position for sewing.

A still further object of the invention is to 50 provide a machine of the above type wherein the sewing head is controlled by one clutch and the carriage traverse by another clutch which is independent of the first-named clutch, and to provide treadle controlled means for actuating the clutches which includes devices which may be readily adjusted and set so that the operator may either start

the carriage and sewing head simultaneously, 55 or actuate the sewing head while the carriage is standing still, or cause the carriage to travel while the sewing mechanism is idle.

A still further object of the invention is to 60 provide a machine of the above type wherein devices are provided for disengaging the clutch which causes the carriage to travel, provided the operator neglects to open the clutch through the treadle control therefor.

A further object of the invention is to 65 provide a machine of the above type wherein carriage traverse power is applied close to the carriage supporting wheels and close to the center of gravity of the carriage unit, so that 70 said carriage will be caused to move smoothly without twisting or tilting of the parts.

A still further object of the invention is to 75 provide a machine of the above type wherein in the tracks for the carriage can be readily raised or lowered for bags of different heights.

These and other objects will in part be obvious and will in part be hereinafter more fully disclosed.

In the drawings which show by way of 80 illustration one embodiment of the invention—

Figure 1 is a front elevation of a filled bag sewing machine embodying the improvements, the sewing head being omitted; 85

Fig. 2 is a plan view of the machine with the sewing head broken away;

Fig. 3 is an enlarged view of the upper portion of the right-hand side of the machine, the sewing head being also broken away in 90 this Figure;

Fig. 10 is a view partly in side elevation and partly in section of the bracket on which the clutches and clutch controlling devices are mounted, and

5 Fig. 11 is a view partly in plan and partly in section of the parts shown in Fig. 10.

The invention is directed broadly to a filled bag sewing machine wherein the carriage is mounted so as to move back and forth on 10 tracks supported at the upper end of the main frame. On this carriage is a sewing head for closing the mouth of the bag, and a motor for actuating the sewing head and for propelling the carriage in one direction. There are two 15 tracks on which the carriage is mounted, but the front track is the main track which carries the weight of the carriage and the parts mounted thereon, so that the machine may, in effect, be said to be a one-track machine. The 20 sewing head and motor are so mounted on the carriage and positioned relative to this track that the motor counterbalances the sewing head, while the sewing head overhangs the main frame of the machine. By 25 this arrangement of the sewing head, said head may be so disposed that the needle is horizontal and the machine is above the bag as it travels across the same for closing the mouth of the bag. The weight of the parts 30 mounted on the carriage are centered close to this front rail of the track. The carriage is propelled along the track in one direction by a rack bar mounted close to the top of this front rail, and by a pinion engaging 35 said rack bar. The pinion is mounted on a vertical shaft which includes a clutch so that the carriage may be connected to or disconnected from the actuating means therefor. The shaft which carries the pinion for propelling the carriage includes a friction connection which slips slightly in the starting 40 of the machine so as to prevent jerking of the parts, and which can slip if the carriage should strike an obstruction so as to prevent 45 the breaking of the parts. The sewing head is driven from a motor by means of a suitable clutch which is independent of the clutch which connects the carriage to the motor. These clutches are controlled from a treadle 50 through a bar mounted on the means which supports the tracks and shiftable endwise thereof. This bar, in its endwise movement, also moves sidewise, and the sidewise movement of the bar presses against the end of a 55 control lever. This control lever operates the clutches, and the operation of the clutches is through yielding devices which are capable of being adjusted and set in different positions. Through this setting of the 60 clutch operating mechanism, the operator, by depressing the treadle, may arrange the parts so as to accomplish one of three things. First, the simultaneous starting of the sewing head and the actuation of the carriage. 65 Second, the starting of the sewing head while

the carriage is standing still. Third, the traveling of the carriage while the sewing head is idle. The tracks and the parts mounted thereon are shiftable toward the front of the machine and away from the front of the 70 machine for positioning the sewing head so that it will overhang the frame of the machine to a greater or less extent. The carriage and the parts carried thereby form a unit which can be removed from the tracks without requiring the disconnection of the devices which control the sewing head or the carriage. The tracks are mounted on brackets at the upper part of the main frame and these brackets can be raised or lowered for changing the height of travel of the carriage. The 75 means for raising and lowering the brackets is housed in one of the vertical columns which supports the brackets, and thus it is that these parts are kept free from dust and dirt. As 80 noted above, the carriage is intended to be positively driven in one direction, and that is, during the sewing of the mouth of the bag. When the seam is finished which closes the 85 bag, then the clutch which causes the carriage to travel is separated, so as to release the carriage from its actuating means. During the forward movement of the carriage, a spring is put under tension, and thus it is that power 90 is stored, so that when the clutch is released 95 which causes the carriage to travel, this stored power is utilized for starting the carriage on its return movement, and the stored power may also be used to press the carriage 100 rearwardly, or to its initial starting position for stitching. The tracks are slightly inclined downwardly toward the initial starting position for stitching.

Referring more in detail to the drawings, the various parts of the machine will be described under different headings, as follows.

Base and frame.

The base of the machine consists of two angle irons 1, mounted on casters 2, and connected by a plate 3, secured thereto by screws 4 to form a platform. Rising from the platform are columns 5. These columns are formed of a main member 6 on which the spacing bars 7 and the cover plates 8 are 110 mounted to form guiding channels for the members 9 and 10 which support the tracks and the mechanism carried thereby. The main members, spacing bars and cover plates are held together by suitable screws 11 (see 115 Figures 7, 8 and 9). A cross brace 12 is provided to properly space and stiffen the upper ends of these columns, thus forming a 120 supporting frame for the machine (see Fig. 1).

125

Elevating mechanism.

The members 10 which slide in the rear guiding channels of the column are provided with rack teeth 13^a which mesh with the 130

pinions 13 keyed on the cross shaft 14. The rear spacing bar in each column is cut away at 15 (see Fig. 7) to provide clearance for the pinions. Mounted on the cross shaft adjacent the left-hand rear cover plate 8 is a pinion 16 which meshes with a pinion 17 mounted on the hand wheel shaft 18 operated by a hand wheel 18^a. On the shaft 18 is a ratchet wheel 19, the teeth of which are engaged by a pawl 20 pivotally mounted on the column. Said pawl is provided with a handle 21 for convenient manipulation. It will be noted that the weight of the tracks and carriage will tend to rotate the shaft 14 in a clockwise direction as viewed in Fig. 4, and this in turn, will cause the hand wheel shaft 18 to tend to turn in a counter-clockwise direction, which tendency is resisted by the pawl 20. It will also be noted that this train of gearing makes an easily operated and speedy means for vertically adjusting the sewing head, which is very simple in construction.

It will be noted in Fig. 7 that the teeth on the member 10 fill up the entire guiding channel and thus prevent the flour or other material being sacked from falling down and clogging the teeth of the pinions 13. The gear 16 and the pinion 17 are likewise protected with a suitable housing 22 (see Fig. 1).

Tracks.

At the upper end of the members 9 and 10 are angle brackets 23 and 24 which are secured thereto by the screws 25. Mounted on the upper faces of these brackets are the cross members 26 and 27 which support the tracks and hold them in alignment. These cross members are secured to the brackets by the screws 28 which pass through the slots 29 in the brackets and screw into the cross members (see Fig. 6). This provides means whereby the tracks and carriage may be adjusted laterally at right angles to the path of travel of the carriage so that the line of stitching can be placed nearer to or farther from the columns, as desired. The cross member 27 is further provided with four set screws 30 which are used to elevate the right hand end of the track to any desired inclination to aid in returning the carriage to the starting position. On the forward end of the cross members is an L-shaped main track member 31, which is secured thereto by the screws 32 and at the rear end of the cross members is a second track 33 secured by the screws 34.

Treadle control.

Extending between the cross members and located between the track members is a control bar 35, the purpose of which will be described hereinafter. This bar is secured to the bosses 36 on the cross members by the screws 37 which pass through the parallel

angular slots 38 in the control bar (see Fig. 5). A tension spring 39 tends to pull the bar to the right as viewed in Fig. 6. The bar is operated by a link 40 which connects it to the arm 41, which arm is mounted on the upper portion of a telescoping rock shaft 42. This upper portion of the rock shaft is mounted in a bearing 43 on the bracket 23 and is secured against endwise movement by a cotter pin located just beneath this bearing. The lower section 44 of this rock shaft slides inside the upper portion and is held in engagement therewith by a spline and key construction. This lower portion is mounted in a bearing 45 located on the left-hand base angle and is held against endwise movement in the bearing by a cotter pin. Mounted on this shaft 44 immediately above this bearing there is an arm 46, the outer end of which is engaged by the outer end of the arm 47 on the treadle shaft 48 (see Fig. 6). This treadle shaft is mounted in the bearings 49 and is held in place by a thrust collar 50. A suitable treadle 51 is mounted on the outer end of the shaft.

Carriage.

The carriage on which the sewing head is mounted consists of an L-shaped main frame 52 on the upper end of which are two forwardly projecting members 53 to which the grooved wheels 54 engaging the main track are attached by bolts 55 (see Figures 4 and 5). The sewing head 56 is secured to the face 57 of the main frame by a bolt 58 and the base of the sewing head is located between the wheels 54 and in the rear of the track to reduce the amount of overhanging weight as much as possible (see Fig. 4). The main carriage frame has a depending member 59 at the rear end thereof to which is secured a roller 60, which roller engages the rear track member 33. There is only one roller 60 and this is located midway between the wheels 54. The carriage is mounted on three points and the wheels are always in contact with the track and the carriage thus prevented from rocking. The grooved wheels will prevent any lateral movement of the carriage. This main carriage frame carries the motor 61 and on the right-hand side also carries the bracket 62 on which bracket the clutches and the controlling mechanism therefor are assembled as a separate unit as shown in Figures 10 and 11.

Sewing head clutch.

The sewing head pulley 63 is driven by a belt 64 which passes over the idlers 65 mounted on the idler bracket 66, which idler bracket is secured to the top of the vertical member 67 at the rear end of the bracket 62 and thence around the driven clutch pulley 68. This driven clutch pulley is freely mounted on the clutch shaft 69 and is provided with a bushing 70 to compensate for wear (see Fig. 10).

This pulley carries a cone-shaped clutch face 71 which is preferably faced with leather or other suitable material. This clutch face engages a clutch face in the driving pulley 72 which pulley is driven by a belt 73 cooperating with a motor pulley 74. This driven pulley is fixed to the shaft 69 by a key 75 and the nut 76. The driven pulley is brought into and out of engagement by the clutch yoke 77, the upper end of which is mounted on a pin 78 located in the idler bracket 66, and the clutch yoke is actuated by a rod 79. Mounted on the hub 80 of the driven clutch pulley 68 is a clutch collar 81 and a thrust washer 82. The thrust collar is provided with oppositely disposed pins 83, the inner ends of which engage the groove 84 formed in the hub 80 and the outer ends of which engage the slots 85 in the clutch yoke (see Fig. 11). It will be noted that the inner ends of these pins are so disposed as to act only on one side of the groove 84 and that their only function is to disengage the clutch in which action comparatively little force is required. In bringing the clutch 25 into engagement where more force is required, the clutch yoke through the outer ends of the pins 83 forces the clutch collar and thrust washer against the adjacent side of the driven clutch pulley and thus applying the end thrust 30 over a greater surface than would be available if the inner ends of the pins 83 were required to engage as well as disengage the clutch. The shaft 69 is mounted in ball bearings 86 and 87 located in the vertical portions 67 and 35 68 and the bracket 62 and is held against end-wise movement by a nut 89 which tends to force the side of the bearing 87 against the shoulder 90 in the recess in which the bearing is located.

40 Carriage driving mechanism.

Mounted on the upper edge of the main track member on the side adjacent the carriage and extending along the major portion 45 of its length is a rack 91, the teeth of which are engaged by the teeth of the pinion 92. This pinion is provided with a shoulder portion 93 which runs in a bearing 94 and at the end thereof, which projects beyond the bearing is provided with clutch jaws 95. These clutch jaws are engaged by the teeth of the sliding clutch member 96. The sliding clutch member is mounted on the shaft 97 and is provided with a spline or keyway which engages 50 the key 98 fixed to the shaft and therefore turns with the shaft. The shaft 97 rotates in the bearing 99 formed in the bracket 62 and at its upper end in the pinion 92 and as the pinion in turn is journaled in the bearing 94, the shaft in effect is journaled in the bearings 94 and 99. Endwise movement of this shaft is prevented by the thrust collar 100 which is fixed to the shaft by a pin 101 and the lower end of the driving flange 102 which is likewise fixed to the shaft by a pin 103. The shaft

is driven by a worm gear 104 which in turn is driven by a spiral gear 105 on the end of the shaft 69. This worm gear is not connected directly to the shaft but is held in frictional engagement with the faces of the driving flanges 102 and 106 by the nut 107. The driving flange 102 is fixed to a shaft by a pin 103 and the flange 106 is fixed to the shaft by a screw 108 which engages a groove 109 formed in the shaft. To prevent 75 undue wear of the friction surfaces, washers 110 of suitable material such as fibre are located between the adjacent faces of the worm gear and the driving flanges. Thus it will be seen that there is not a positive drive between 80 the shaft 69 and 97. The purpose of this friction drive is two-fold: First, to take up by slippage the shock of starting the carriage along the track, and second, to provide a means which will slip in case the drive should 85 become obstructed and by such slippage prevent the breakage of parts. Also it will be noted that by adjusting the nut 107, the amount of pressure between the driving flanges and the worm gear can be varied and 90 that wear on the washer 110 can be taken up. A further advantage in this friction drive lies in the fact that the starting of the carriage without undue shock on the driving mechanism is not dependent on the skill of the operator in operating the foot treadle. In other words, the amount of slippage can be adjusted and will then be uniform regardless of the way the foot treadle is operated.

100 Clutch operating mechanism.

Mounted on the pivot 111 on the bracket 62 is a lever 112, the lower end of which is provided with a roller 113, which roller is held against the adjacent face of the control bar 105 35 by the tension spring 114, one end of which is attached to the top of the lever at 115, and at its other end is attached to the bracket 62 by a stud 116. The upper end of this lever engages the sewing head clutch control rod 110 79 and the carriage traverse or jaw clutch control rod 117, which rods pass through parallel holes in the upper end of the lever. These rods are held in adjusted position relative to the lever by lock nuts located on either 115 side of the lever and springs 118 are interposed between the lever and one pair of lock nuts on each rod to provide a flexible connection between the lever and each clutch. The action of these springs will be described in 120 connection with the description of the operation of the machine. The rod 117 is attached to the arm 119 of the jaw clutch yoke 120 by a bolt 121. This clutch yoke is pivotally mounted at 122 on the bracket 62 and the yoke is provided with projecting lugs 123 which engage the groove 124 of the sliding jaw clutch member 96 on opposite sides thereof and bring it into and out of engagement with the pinion 92. It will be noted 130

that the shafts 69 and 97 together with the clutches and gearing carried thereby and the clutch operating mechanism, are all mounted on the bracket 62 forming a separate unit 5 which is attached to the main frame of the carriage by the bolts 125.

Carriage traverse control and carriage return.

Sliding in guide blocks 126 and 127 which 10 are mounted beneath the rack 91 and along side of the main track member 31 is a rod 128 which is surrounded by a compression spring 129. This spring at one end presses against the guide block 126 and at its other end is 15 attached to the rod 128. The end of the rod which projects through the block 126 is bent away from the main track member to form a projecting lug 130. The spring as shown in Fig. 5 is wound with a minimum number 20 of coils to permit a great degree of compression. The action of this spring and rod is as follows: When the treadle is depressed, the sewing head begins to operate and the carriage moves along the track from left to 25 right as viewed from the front of the machine. As the carriage approaches the end of its travel, the lug 130 of this spring pressed rod is engaged by the bearing 99 (see Fig. 10) on the clutch bracket 62 and the rod 30 is moved endwise with the carriage, compressing the spring 129. When the treadle is released, the power stored in this spring gives the carriage its initial start in returning to the starting position at the left. The tracks 35 are inclined and this incline causes the carriage to return to the starting position by gravity. It will be noted that the use of this spring pressed rod accomplishes two functions. It permits a smaller degree of incline 40 to be used and it decreases the time necessary for the carriage to return.

Mounted on the horizontal portion of the main track member is a stop block 131 which is provided with a spring 132 projecting toward the carriage. The free end of this 45 spring engages the main frame of the carriage when the starting point is reached and acts as a cushion in stopping the carriage. Additional holes 133 in the main frame member are provided so that the starting point 50 may be varied.

On the extreme right-hand end of the main track member is a block 134, the lower face of which is inclined. The purpose of this 55 block is to engage the arm 135 (see Fig. 10) which projects from the left-hand lug of the clutch yoke 120 and forces the sliding clutch member down out of engagement with the pinion when the carriage reaches the 60 extreme right-hand end of the track and thus prevents the carriage from running off the end of the track if by any chance the operator should forget to release the treadle or the clutch mechanism become obstructed in any 65 way.

Operation of the machine.

When the treadle is depressed, the control bar 35 through the mechanism connecting it to the treadle is moved to the left as viewed in Fig. 2, and against the force exerted by the spring 39. Due to the angular slots 38, however, the bar also moves bodily to the left as viewed in Fig. 3, and this movement causes the lever 112 to move the clutch control rods 79 and 117 to the right as viewed 70 in Figures 3, 10 and 11, and by this movement, bring the clutches into engagement causing the sewing head to operate and the carriage to move along the tracks. 75

Under certain conditions, for instance, when sewing narrow bags, it is desirable first to engage the carriage traverse clutch to bring the sewing head up to the bag before starting to sew and then by further depressing the treadle, to engage the sewing head clutch. To accomplish this, the lock nuts adjacent the spring 118 on the clutch rod 79 would be adjusted away from the lever 112. Then, when the treadle is depressed, the lever 112 will first engage the carriage traverse clutch and then when the treadle is further depressed, the lever will compress the spring on the clutch rod 117 and engage the spring on the clutch rod 79 and bring the sewing 90 head clutch into engagement. 95

Under other conditions, especially when sewing bags of greater width than the travel of the sewing head, it is desirable first to start the sewing head and then, by further depressing the treadle, to bring the carriage traverse clutch into operation. To accomplish this, the lock nuts adjacent the spring 118 on the clutch rod 117 would be adjusted farther away from the lever than the similar lock nuts on the clutch rod 79. With this adjustment, when the treadle is partly depressed, the sewing head clutch will be brought into operation and when the treadle is further depressed, the lever 112, moving to the right as viewed in Figures 3, 10 and 11, will compress the spring on the clutch rod 79 and bring the carriage traverse clutch into operation. The spring 118 on the clutch rod 117 has an additional function which is to make a flexible connection between the treadle and the clutch jaws so that if the teeth on the sliding clutch member 96 should come in contact with the flat portion of the end of the pinion 93 between the jaws the spring will bring the clutch into proper engagement when the teeth coincide. 110

In the case of sewing very small bags, it is found better to leave the sewing head stationary and to allow the feed of the sewing head to move the bags. To accomplish this, it is only necessary to adjust the lock nuts on the clutch rod 117 away from the lever 112 to a point where the lever will not operate the clutch for the carriage. 125 130

From the above, it will be apparent that a filled bag sewing machine has been provided wherein the sewing head can be set so as to travel at different distances from the main frame for stitching bags of different sizes. This is brought about by adjusting the blocks which support the tracks at the top of the main frame. The bodily shifting of the tracks includes also the shifting of the carriage on which the sewing head and motor are mounted, and it furthermore includes the shifting of the control bar, which shifting does not in any way effect the treadle connection therewith for the reason that this bar is connected by a link to the arm which is actuated by the treadle. Furthermore, it will be noted that the sewing head which overhangs the front of the machine is counterbalanced by the motor so that the weight of the parts carried by the carriage are very nearly equally distributed adjacent the front rail on which the carriage travels. There are two wheels supporting the carriage at the front side thereof, while the wheel at the back of the carriage is mainly for preventing the tilting of the carriage. The machine is, in substance, a one rail machine, as all the weight is practically carried by the front rail. The power for causing the carriage to move is applied very close to the wheels which support the carriage on the front rail, and also very close to the center of gravity of the weight which is moved. Inasmuch as the lever which shifts the clutches is merely moved by the sidewise movement of the control bar, it is noted that the carriage with the motor and sewing head may be lifted as a unit from the tracks without disturbing any control connections for the actuating parts. It will be noted also that the two clutches, one of which controls the sewing head and the other the carriage, are independent of each other and so controlled that, if desired, these clutches may be simultaneously closed, or, if desired, the sewing head clutch may be closed first, and the clutch for causing the motor to actuate the carriage closed at some subsequent time thereafter by further depressing of the treadle. This is useful in sewing extremely large bags where the capacity of the machine is hardly sufficient for the carriage to travel across the top of the bag, and therefore, some portion of the bag at the starting must be stitched before the carriage is caused to travel and thus finish the stitching of the mouth of the bag. Then again, the clutches may be set so as to start the carrier first, when the treadle is depressed a slight distance, and subsequently thereto, the sewing head started by a further depressing of the treadle. This is extremely useful where the bags are relatively small, and therefore, it is desirable to run the carriage for a slight distance before beginning the stitching operation. It will be noted also that the carriage is positively moved during the stitching of the bag, after which the actuating mechanism for the carriage is disconnected so that the carriage may be moved back by hand or by gravity, or by stored power, or by stored power and gravity. The last is the preferred form of the present invention, and this is brought about by the rod being engaged by the carriage and moved therewith, which compresses the spring, and the power stored in the spring during the compressing thereof is utilized to start the carriage on its return, and to facilitate the return of the carriage to its initial starting position for stitching. The track is slightly inclined so that gravity aids in the return of the carriage. It will be noted also that the tapered block is provided for disconnecting the clutch which operates the carriage, provided the operator fails to depress the treadle for stopping the machine when the filled bag is closed. This is to prevent the carriage from being propelled beyond the limit of its travel, and thus causing the jamming or breaking of the parts.

It is obvious that minor changes in the details of construction may be made without departing from the spirit of the invention as set forth in the appended claims.

Having thus described the invention, what we claim as new and desire to secure by Letters-Patent, is:

1. A filled bag sewing machine comprising a supporting frame, tracks mounted on said frame, a carriage movable on said tracks, a sewing head and actuating devices for said head and carriage mounted on said carriage, said sewing head overhanging the supporting frame, means for supporting said tracks whereby the tracks may be bodily adjusted horizontally transversely of the direction of travel of the carriage for shifting the path of travel of the sewing head relative to the supporting frame, a control bar for controlling the actuating mechanism for the sewing head and carriage mounted on and shiftable with said tracks, and treadle actuated devices connected to said control bar for moving the control bar, said last-named devices including a link connected to the control bar so as to permit the lateral shifting of the control bar.
2. A filled bag sewing machine comprising a supporting frame, tracks mounted on said frame, a carriage movable on said tracks, a sewing head and actuating devices for said head and carriage mounted on said carriage, said sewing head overhanging the supporting frame, means for supporting said tracks whereby the tracks may be bodily adjusted horizontally transversely of the direction of travel of the carriage for shifting the path of travel of the sewing head relative to the supporting frame, said main support including spaced columns each of which is provided with vertically movable supporting

- members on which the tracks are mounted, means for raising or lowering said vertically movable members, said last-named means including a rack formed on one of said vertically moving members, a pinion mounted on the lower section of the support and meshing with said rack, and a hand wheel mounted on said lower section of the support and connected to said pinion for turning the same.
10. 3. A filled bag sewing machine comprising a supporting frame, tracks mounted on said frame, a carriage movable on said tracks, a sewing head and actuating devices for said head and carriage mounted on said carriage, said sewing head overhanging the supporting frame, means for supporting said tracks whereby the tracks may be bodily adjusted horizontally transversely of the direction of travel of the carriage for shifting the path 15 of travel of the sewing head relative to the supporting frame, said main support including spaced columns, each of which is provided with vertically movable supporting members on which the tracks are mounted, 20 means for raising or lowering said vertically movable members, said last-named means including a rack formed on one of said vertically moving members, a pinion mounted on the lower section of the support 25 and meshing with said rack, and a hand wheel mounted on said lower section of the support and connected to said pinion for turning the same, said pinion and rack being housed within the lower section of the support.
30. 4. A filled bag sewing machine comprising a main supporting frame, tracks mounted thereon, a carriage movable on said tracks, a sewing head mounted on said carriage and overhanging the supporting frame in front 35 of the tracks, a motor mounted on said carriage, devices actuated by said motor for moving the carriage positively in one direction along the tracks, said devices including friction driving means capable of slipping during the starting of the carriage or in case of 40 emergency, and a clutch independent of the friction driving means whereby said actuating devices may be disconnected from the carriage.
45. 5. A filled bag sewing machine comprising a main supporting frame, tracks mounted thereon, a carriage movable on said tracks, a sewing head mounted on said carriage and overhanging the supporting frame in front 50 of the tracks, a motor mounted on said carriage, devices actuated by said motor for moving the carriage positively in one direction along the tracks, said devices including friction driving means capable of slipping during 55 the starting of the carriage, or in case of emergency, and also a clutch whereby said actuating devices may be disconnected from the carriage, and independent means for actuating the sewing mechanism from 60 said motor including a clutch whereby said 65 sewing head may be disconnected from the motor.
6. A filled bag sewing machine comprising a main supporting frame, tracks mounted thereon, a carriage movable on said tracks, a sewing head mounted on said carriage and overhanging the supporting frame in front of the tracks, a motor mounted on said carriage, devices actuated by said motor for moving the carriage positively in one direction 70 along the tracks, said devices including friction driving means capable of slipping during the starting of the carriage, or in case of emergency, and also a clutch whereby said actuating devices may be disconnected from the carriage, 75 independent means for actuating the sewing mechanism from said motor including a clutch whereby said sewing head may be disconnected from the motor, and treadle controlled means for actuating the clutches, said treadle controlled means including yielding members capable of being adjusted and set so that the clutches may be operated simultaneously or independently.
7. A filled bag sewing machine comprising a support, tracks mounted on said support, a carriage movable on said tracks, a sewing head mounted on said carriage and overhanging said main supporting frame, a motor mounted 80 on said carriage, devices actuated by the motor including a clutch, devices actuated by said motor for positively moving said carriage in one direction along the tracks, said devices including a clutch, devices actuated by said motor for operating the sewing head, treadle controlled means for disengaging the clutch connecting the motor to the carriage actuating means, said tracks being inclined downwardly toward the initial starting point for stitching whereby said carriage is returned by gravity when the clutch is disconnected.
8. A filled bag sewing machine comprising a support, tracks mounted on said support, a carriage movable on said tracks, a sewing head mounted on said carriage and overhanging said main supporting frame, a motor mounted 85 on said carriage, devices actuated by the motor for positively moving said carriage in one direction along the tracks, said devices including a clutch, devices actuated by said motor for operating the sewing head, treadle controlled means for disengaging the clutch connecting the motor to the carriage actuating means, said tracks being inclined downwardly toward the initial starting point for stitching whereby said carriage is returned by gravity when the clutch is disconnected, and a yielding stop shiftable to various set positions for stopping the return of the carriage.
9. A filled bag sewing machine comprising 90 a support, tracks mounted on said support, a carriage movable on said tracks, a sewing head mounted on said carriage and overhanging said main supporting frame, a motor mounted on said carriage, devices actuated by the mo-

- tor for positively moving said carriage in one direction along the tracks, said devices including a clutch, devices actuated by said motor for operating the sewing head, treadle controlled means for disengaging the clutch connecting the motor to the carriage actuating means, said tracks being inclined downwardly toward the initial starting point for stitching whereby said carriage is returned by gravity when the clutch is disconnected, and means in which power is stored during the forward movement of the carriage when moved by the motor for aiding in the starting of the return of the carriage when the clutch is disconnected.
10. A filled bag sewing machine comprising a support, tracks mounted on said support, a carriage movable on said tracks, a sewing head mounted on said carriage and overhanging said main supporting frame, a motor mounted on said carriage, devices actuated by the motor for positively moving said carriage in one direction along the tracks, said devices including a clutch, devices actuated by said motor for operating the sewing head, treadle controlled means for disengaging the clutch connecting the motor to the carriage actuating means, said tracks being inclined downwardly toward the initial starting point for stitching whereby said carriage is returned by gravity when the clutch is disconnected, and means in which power is stored during the forward movement of the carriage when moved by the motor for aiding in the starting of the carriage when the clutch is disconnected, said last-named means being constructed so that the stored power operates during substantially the entire return movement of the carriage to facilitate the return of the carriage by gravity.
11. A filled bag sewing machine comprising a main supporting frame, tracks carried thereby, a carriage movable on said tracks, a sewing head mounted on the carriage, a motor mounted on the carriage, a transverse shaft mounted on the carriage and connected to said motor, a friction clutch mounted on said shaft and including a loose belt wheel connected to the sewing head, a vertical shaft mounted on said carriage, said vertical shaft being geared to said transverse shaft whereby the vertical shaft is actuated thereby, a pinion freely mounted on said vertical shaft, a rack extending lengthwise of the front rail of the track and secured thereto in which said pinion meshes, a clutch member keyed to said vertical shaft and adapted to engage said pinion for connecting the pinion to the vertical shaft and thus causing the carriage to be operated by the motor.
12. A filled bag sewing machine comprising a main supporting frame, tracks carried thereby, a carriage movable on said tracks, a sewing head mounted on the carriage, a transverse shaft mounted on the carriage and connected to said motor so as to be operated continuously thereby, a friction clutch mounted on said shaft and adapted to be connected thereto, said friction clutch including a belt pulley
- motor mounted on the carriage, a transverse shaft mounted on the carriage and connected to said motor, a friction clutch mounted on said shaft and including a loose belt wheel connected to the sewing head, a vertical shaft mounted on said carriage, said vertical shaft being geared to said transverse shaft whereby the vertical shaft is actuated thereby, a pinion freely mounted on said vertical shaft, a rack extending lengthwise of the front rail of the track and secured thereto in which said pinion meshes, a clutch member keyed to said vertical shaft and adapted to engage said pinion for connecting the pinion to the vertical shaft and thus causing the carriage to be operated by the motor, a connection between said vertical shaft and said transverse shaft including members having frictional engagement with each other, whereby the vertical shaft has a certain amount of slippage relative to the transverse shaft during the starting of the carriage and in case the carriage strikes an obstruction.
13. A filled bag sewing machine comprising a supporting frame, tracks mounted thereon, a carriage movable on said tracks, a sewing head mounted on the carriage, a motor mounted on the carriage, a transverse shaft mounted on the carriage and connected to said motor so as to be operated continuously thereby, a friction clutch mounted on said shaft and adapted to be connected thereto, said friction clutch including a belt pulley connected to the sewing head, a vertical shaft geared to said transverse shaft, a pinion mounted on said vertical shaft and adapted to engage a rack bar mounted on the frame for propelling said carriage in one direction, a clutch for connecting said vertical shaft to said pinion, a transverse bar adapted to close the friction clutch, a swinging lever having an opening through which said bar passes, adjustable nuts on said bar at each side of said lever, a spring between one of said adjustable nuts and the lever, a second transverse bar passing through the opening in said lever, nuts on said second transverse bar on opposite sides of the lever, and a spring between one of said nuts and the lever, both of the springs on the bars being on the same side of the lever, an elbow lever connected to the last-named bar and to the clutch on the vertical shaft, whereby when said lever is swung in one direction, it will compress the springs for closing the clutches.
14. A filled bag sewing machine comprising a supporting frame, tracks mounted thereon, a carriage movable on said tracks, a sewing head mounted on the carriage, a motor mounted on the carriage, a transverse shaft mounted on the carriage and connected to said motor so as to be operated continuously thereby, a friction clutch mounted on said shaft and adapted to be connected thereto, said friction clutch including a belt pulley

connected to the sewing head, a vertical shaft 5
geared to said transverse shaft, a pinion
mounted on said vertical shaft and adapted
to engage a rack bar mounted on the frame
5 for propelling said carriage in one direction,
a clutch for connecting said vertical shaft to
said pinion, a transverse bar adapted to close
the friction clutch, a swinging lever having
an opening through which said bar passes, ad-
10 justable nuts on said bar at each side of said
lever, a spring between one of said adjustable
nuts and the lever, a second transverse bar
passing through the opening in said lever,
nuts on said second transverse bar on opposite
15 sides of the lever, a spring between one of
said nuts and the lever, both of the springs
on the bars being on the same side of the lever,
an elbow lever connected to the last-named
bar and to the clutch on the vertical shaft,
20 whereby when said lever is swung in one di-
rection, it will compress the springs for clos-
ing the clutches, the extent of adjustment of
the nuts against which the springs bear being
such that they may be positioned so that the
25 lever, when shifted, will simultaneously close
both clutches, or will close either clutch be-
fore the other clutch is closed.

15. A filled bag sewing machine comprising
a support, tracks mounted on said sup-
port, a carriage movable on said tracks, a
sewing head mounted on said carriage and
overhanging said support, devices for moving
30 said carriage along said tracks, devices
for operating said sewing head, a motor
mounted on said carriage and movable there-
with, clutches for connecting and disconnecting
said motor to said carriage moving de-
35 vices and said sewing head operating devices,
and treadle operated means for connecting
and disconnecting said clutches, said treadle
operated means including devices capable of
adjustment whereby either clutch may be en-
40 gaged before the other clutch is engaged or
where both clutches may be simultaneously
engaged.

16. A filled bag sewing machine compris-

ing a support, tracks mounted on said sup-
port, a carriage movable on said tracks, a
sewing head mounted on said carriage and
overhanging said support, a motor mounted
50 on said carriage, devices actuated by the
motor for moving the carriage in one direc-
tion along the tracks, said tracks being in-
clined downwardly toward the initial start-
ing point for stitching means for varying the
55 amount of inclination of the tracks, means
for disconnecting the carriage from the motor
so as to permit the same to return by gravity
to its starting point, and means in which
power is stored during the forward move-
60 ment of the carriage when connected to the
motor for aiding in the return of the carriage
when the clutch is disconnected.

17. A filled bag sewing machine comprising
a base, a vertically adjustable frame struc-
ture mounted on said base, tracks mounted on
said vertically adjustable frame structure,
a carriage movable on said tracks, a sewing
head and actuating devices for said head and
carriage mounted on said carriage, said sew-
ing head overhanging the frame structure,
means for supporting said tracks on said
frame structure whereby the tracks may be
adjusted bodily horizontally transversely of
the direction of travel of the carriage, and
70 treadle actuated devices for controlling the
actuating mechanism for the sewing head
and carriage including a treadle mounted on
said base, a control device mounted on the
adjustable frame structure and connected to
75 the actuating mechanism for the sewing head
and carriage so as to permit the bodily shift-
ing of the tracks, and means for connecting
said control device to said treadle constructed
so as to permit the raising and lowering of
80 the adjustable frame without disturbing the
treadle connections.

In testimony whereof we affix our signa-
tures.

NORMAN V. CHRISTENSEN.
WALTER M. HANNEMAN.
